UNITED STATES PATENT OFFICE.

JOHN J. KELLER, OF COLUMBUS, OHIO.

DESIGN FOR A TOY AIRPLANE.

57,437.

Specification for Design.

Patented Mar. 29, 1921.

Application filed June 16, 1919. Serial No. 304,709. Term of patent 3½ years.

To all whom it may concern:

Be it known that I, JOHN J. KELLER, a citizen of the United States, residing at Columbus, in the county of Franklin and State of Ohio, have invented a new, original, and ornamental Design for a Toy Airplane, of which the following is a specification, reference being had to the accompanying drawing, forming a part thereof.

The figure is a perspective view of the toy airplane.

I claim:

The ornamental design for a toy airplane, as shown.

JOHN J. KELLER.

Witnesses:

C. C. SHEPHERD,
M. A. STEPHENS.
